PROTECTIVE EQUIPMENT

Wesley C. Thompson, St. Louis, Mo.

Application August 24, 1949, Serial No. 112,135

2 Claims. (Cl. 150—52)

This invention relates to improvements in protective equipment. More particularly this invention relates to improved protective equipment that can be used by newspaper vendors.

It is therefore an object of the present invention to provide an improved protective cover for use by newspaper vendors.

Newspapers are frequently printed and sold so rapidly that the ink on the paper does not have sufficient time to dry. As a result, newspaper vendors, who hold the newspapers under their arms while they attempt to vend them find that the ink rubs off of the newspapers and onto their clothing. This ink is dark, and it quickly discolors the clothing; making the clothing unattractive and unusable for general wear. Moreover, the discoloration of the clothing of the newspaper vendors detracts seriously from the overall appearance of the newspaper vendors. The present invention obviates discoloration of the clothing of newspaper vendors by providing a protective cover which can be interposed between the newspapers held by the newspaper vendor and the vendor's clothing. While the ink may still rub off of the newspapers, it will rub off onto the protective cover and not onto the clothing of the newspaper vendor. It is therefore an object of the present invention to provide an improved protective cover that can be used by newspaper vendors to protect their clothing against the ink on newspapers.

It is necessary for the newspaper vendor to have ready access to the newspapers which he wishes to vend, and yet those papers should be kept from discoloring his clothing. The present invention makes it possible to satisfy both of these requirements by providing a panel which can be interposed between the newspapers held by the vendor and the sleeve of the vendor's coat or shirt, and which has a cut-away corner. The cut-away corner will facilitate ready grasping of the newspapers by the vendor, and yet it will not permit discoloring of the vendor's clothing, because it will be at one end of the panel and thus spaced from the vendor's arm. It is therefore an object of the present invention to provide a panel which can be interposed between the sleeve of the vendor's coat or shirt and the newspapers, and which has a cut-away corner.

The protective cover provided by the present invention has a generally-rectangular panel in addition to the panel with the cut-away corner. This generally rectangular panel will be interposed between the vendor's body and the newspapers, while the panel with the cut-away corner will be interposed between the vendor's arm and the newspapers. The vendor's body, being thicker than the vendor's arm, will be fully protected against contact with the newspapers by the generally rectangular panel; the vendor's arm, being smaller, will be fully protected against contact with the newspapers by the panel with the cut-away corner. It is therefore an object of the present invention to provide a protective cover which has a generally-rectangular panel and a panel with a cut-away corner.

The protective cover provided by the present invention has a flexible flap which can be placed over the upper edges of the newspapers during rain or snow, but which can be folded back out of the way in good weather. This flap can have a snap fastener thereon that will enable part of the flap to be folded back and held; that part of the flap being held back during mists or light snows. This flap will protect the newspapers against the elements. It is therefore an object of the

present invention to provide a protective cover, for use by newspaper vendors, which has a flap that can be placed over the papers in bad weather, can be partially folded back in damp weather, and can be folded out of the way in fair weather.

The generally-rectangular panel and the panel with the cut-away corner are held together by spaced flexible strips. The spacing of the strips is important since it must permit the vendor to reach between the strips and directly grasp the newspapers with his hand. In the absence of such spacing, the newspapers might slide out from between the two panels of the protective cover. It is therefore an object of the present invention to provide a protective cover, for use by newspaper vendors, which has two flexible strips that extend between and connect the panels of the cover but are spaced apart to enable the vendor to grasp the newspapers.

The protective cover provided by the present invention is additionally useful in protecting the print on the newspaper against smudging. It frequently happens, on hot days, that the perspiration on the vendor's sleeve will cause the ink on the newspapers to become smudged. This smudging of the print is objectionable; partially because it detracts from the appearance of the newspaper, but principally because it makes the reading of the material on the front page of the newspaper difficult. The smudging of the print on any page of the newspaper would be undesirable, but that smudging is particularly undesirable on the front page since that page is supposed to carry the most important news of the day. The present invention minimizes such smudging by spacing the vendor's arm or sleeve away from the newspapers.

Other and further objects and advantages of the present invention should become apparent from an examination of the drawing and accompanying description.

In the drawing and accompanying description a preferred embodiment of the present invention is shown and described but it is to be understood that the drawing and accompanying description are for the purpose of illustration only and do not limit the invention and that the invention will be defined by the appended claims.

In the drawing Fig. 1 is a view of the protective cover provided by the present invention as that protective cover is unfolded and laid out flat.

Fig. 2 is a perspective view of the cover of Fig. 1 as it will appear when used in fair weather.

Fig. 3 is a perspective view of the protective cover of Figs. 1 and 2 as it will appear when used in bad weather, and

Fig. 4 is a perspective view of the protective cover of Figs. 1-3 as it will appear when used in damp weather.

Referring to the drawing in detail, the numeral 10 denotes a frame which is enclosed within a fabric cover 12. The frame 10 is preferably made of a light-weight steel that is welded to give it rigidity and stiffness; however that frame can be made of other materials. The frame 10 has a cut-away corner that stops short of the longitudinal center of the frame. The fabric cover 12 has a cut-away corner, and that cover closely fits the frame 10; the cover 12 and the frame 10 constituting a sturdy panel with a cut-away corner. The panel formed by cover 12 and frame 10 will be substantially the size of a newspaper page folded in half. This panel will be the front panel of the protective cover provided by the present invention, and it will be interposed between the arm of the newspaper vendor and the papers held by that arm.

Two strips 14, preferably of fabric, are secured to the fabric cover 12, and these strips will hold the front and rear panels of the protective cover against separation and loss. These strips 14 are spaced apart to form an opening through which the vendor's hand can be inserted to directly grasp the newspapers encased by the protective cover of the present invention. If desired, a single connector of shorter length than the protective cover could be substituted for the strips 14. The strips 14 are connected to a fabric cover 18 for a rectangular frame 16. The frame 16 also is preferably made of a light-weight steel which is welded to provide a rigid and sturdy construction; but it too can be made of other materials. The frame 16 and the fabric cover 18 constitute the rear panel of the protective cover provided by the present

invention, and that panel will be sturdy and can be interposed between the vendor's body and the newspapers pressed against that body.

A flexible flap 20, preferably of fabric, is secured to the fabric cover 18. The fabric flap 20 is provided with folded seams 22 to avoid raw edges. In the case of fabric covers 12 and 18, raw edges are avoided by sewing those covers so the seams at the exposed edges are internal seams. The covers 12 and 18 are preferably formed as sacks or bags, have the frames 10 and 16 inserted within them, and have their open edges sewn or cemented closed. The flap 20 can be folded back against the rear panel, it can be folded over the top edges of the newspapers, or it can be placed over the upper edges of the newspapers and yet have one corner thereof folded back.

Complementary snap fasteners 24 and 26 can be secured to the flap 20; and the snap fastener 24 can be moved adjacent to, and secured to, the snap fastener 26 by folding one corner of the flap 20 back. Where such folding is neither required nor desired, the snap fasteners 24 and 26 can be separated and the flap 20 permitted to be flat.

It is preferable to make the panels of the protective cover as fabric-encased metal frames, because such panels are light in weight, readily washed, and are not cold to the touch. However, if desired, the panels could be made of sheet metal, wood, pressed paper, plastic-impregnated cloth or paper, or the like.

In using the protective cover provided by the present invention, a news vendor will, in fair weather, fold the flap 20 back against the rear panel, as shown in Fig. 2. Thereafter he will place the newspapers 28 between the front and rear panels, he will place the rear panel against his body, place his arm against the front panel, and insert his hand into the opening between strips 14. That hand will hold the newspapers against falling, and the panels will hold the newspapers flat while protecting the vendor's clothing against discoloration and protecting the print against smudging due to perspiration. The connecting strips 14 may droop down below the bottoms of the newspapers 28, but that is not important since the principal support for the newspapers 28 will come from the vendor's hand and the front and rear panels. The cut-away corner of the front panel will enable the vendor to grasp the upper edges of the newspapers 28 and hand them to the purchasers.

In bad weather, the flap 20 will be folded over the tops of the newspapers 28, as shown particularly in Fig. 3. That flap will then shed rain or snow which would otherwise strike the newspapers. The flap 20 will lie loosely against the front panel, and thus the newspaper vendor can easily reach under the flap 20 and withdraw one or more newspapers, as desired.

In misty weather, the vendor can move the snap fastener 24 into engagement with the snap fastener 26, as shown particularly in Fig. 4. At such times, the flap 20 will shed the moisture that collects on it, and yet it will provide even more ready access to the newspapers 28 than it could when in the position shown in Fig. 3.

The only direct contact which the newspaper vendor need have with the newspapers 28 will be with his hands. One hand will extend through the opening between connecting strips 14 to underlie and support the bottom edges of newspapers 28, and the other hand will grasp those corners of newspapers 28 which are exposed by the cut-away corner of the front panel. All other contact with the newspaper can be had indirectly through the medium of the protective cover. In this way the newspaper vendor can protect his clothing from the ink on the newspapers.

Whereas a preferred embodiment of the present inven-

tion has been shown and described in the drawing and accompanying description it should be obvious to those skilled in the art that various changes can be made in the form of the invention without affecting the scope thereof.

What I claim is:

1. A protective cover for newspapers which can facilitate the vending of newspapers without any soiling or discoloring of the clothing of the newspaper vendor and which comprises a rear panel dimensioned to be disposed between the body of the newspaper vendor and the newspapers to be sold, said panel being a fabric-covered frame of metal, said panel being substantially coextensive with the newspapers to be sold, a front panel dimensioned to be disposed between the arm of the newspaper vendor and the newspapers to be sold, said front panel being a fabric-covered frame of metal, said front panel having a cut-away corner to facilitate grasping of the newspapers to be sold, said cut-away corner stopping short of the longitudinal center of said front panel, connecting strips secured to each of said front and rear panels and maintaining said panels in assembled relation, said strips being flexible, said strips being spaced apart a distance sufficient to permit the newspaper vendor's hand to pass through and to grasp the lower edges of the newspapers to be sold, a flexible flap connected to the upper edge of said rear panel and adapted to overlie the upper edges of the newspapers to be sold, and fasteners on said flap that can hold a corner of said flap folded back, said fasteners being spaced relative to said cut-away corner of said front panel so the folded corner of the flap is adjacent the cut-away corner of the front panel, said flap being foldable back to uncover the upper edges of newspapers disposed between said front and rear panels.
2. A protective cover for newspapers which can facilitate the vending of newspapers without any soiling or discoloring of the clothing of the newspaper vendor and which comprises a rear panel dimensioned to be disposed between the body of the newspaper vendor and the newspapers to be sold, said panel being a fabric-covered frame of metal, said panel being substantially coextensive with the newspapers to be sold, a front panel dimensioned to be disposed between the arm of the newspaper vendor and the newspapers to be sold, said front panel being a fabric-covered frame of metal, said front panel having a cut-away corner stopping short of the longitudinal center of said front panel, connecting strips secured to each of said front and rear panels and maintaining said panels in assembled relation, said strips being flexible, said strips being spaced apart a distance sufficient to permit the newspaper vendor's hand to pass through and grasp the lower edges of the newspapers to be sold, and a flexible flap adapted to overlie and protect the upper edges of newspapers disposed between said front and rear panels, said flap being foldable back to uncover the upper edges of newspapers disposed between said front and rear panels.
